UNITED STATES PATENT OFFICE.

WALTER B. FOGH, OF SEATTLE, WASHINGTON.

OIL BURNER.

Application filed August 23, 1927. Serial No. 214,899.

My invention relates to oil burners and particularly to oil burners of a type which are adapted for use in relatively small furnaces, such, for instance, as in the heating 5 of private residences. It is, however, adapted for use in large sizes.

The object of my invention is to provide a burner of a type of construction and operation which will be simple, easily taken care 10 of and operated and one possessing certain features of automatic adjustment as between the oil and air supply and a burner which is easily installed.

Other objects of my invention will appear 15 from study of the following specification.

This invention consists of a burner employing a rotative or centrifugal oil distributor and one which has an air supply nozzle surrounding said distributor, together 20 with a fan wheel located in the air supply leading to the nozzle and rotated thereby, which fan is connected with and operates the oil distributor.

In the accompanying drawings I have 25 shown my invention in a preferred type of construction.

Figure 1 is a transverse section of the burner taken through the plane which includes the oil controlling valve. Figure 2 30 is a central longitudinal section.

The burner employs a casing or shell, one which at its inner end has a tapering conical shape as shown at 10. Within this shell and axially positioned with relation thereto, 35 is a core 2 which is axially bored to accommodate the shaft 30 of the rotative oil distributor 3. This core 2 is connected with the outer shell by arms 20, of which one is bored to provide an oil supply passage 21.

40 This radially extending portion of the oil supply passage communicates with a port 22, which extends lengthwise of the core at the upper side thereof. The discharge end of this port or passage 22, is at the inner end 45 of the burner core.

The inner end of the core is provided with a conical bore 23 in which is placed the conical head of the oil distributor 3. This head 3 is secured to one end of a shaft 30, 50 the other end of said shaft projecting into a cylindrical chamber 11, formed by the outer end of the casing 1 and a cap or extension 4 secured thereto.

55 Secured to the rear or outer end of the shaft 30 and in chamber 11, is a fan wheel 5. The air for combustion is supposed to

be provided under sufficient pressure to cause a rapidity of flow sufficient to rotate the wheel 5 by its passage thereby and in doing so rotates the oil distributor 3.

60 Located in the outer section of the casing member 4, is an air controlling valve 40, this being of the type ordinarily referred to as a butterfly valve. This is secured upon a stem 41, which extends without the casing 65 and has an arm 42 extending laterally therefrom, forming a crank arm from which it is controlled. The air supply pipe 43 which is secured to the outer section 4 of the casing communicates with a convenient source of 70 supply of air under pressure. This source may consist conveniently of a rotative fan or of a pump.

75 The body of the casing 1, has a bore extending transversely of the portion 21 of the oil supply channel and from one side to the other of the casing. This bore 6 receives a rod 60 which functions as an oil controlling valve. This rod has a port 61, extending transversely therethrough and positioned so 80 as to register with the passage 21 of the oil supply. The rod 60 has an arm 62 extending laterally therefrom and forming a crank arm by which it may be rocked.

85 This arm 62 and the arm 42 of the air controlling valve 40, are connected so as to be operated together. This has been done by putting a thimble or bolt 44 upon the arm 42, said bolt being provided with a hole tapped to receive the arm 62. Stops 63 and 90 64 are adjustably secured upon the arm 62 so as to limit the travel of the bolt 44 thereon. This bolt 44 slides freely upon the arm 62.

95 It is evident that if one of these arms is swung upon its axis the other is swung. These are connected so that as the air valve is moved to contract the passage and to thereby reduce the volume of air delivered, the oil valve is turned so as to similarly 100 contract or reduce the area through which the oil is supplied. The intention is to have such a relation between the two valves that reduction in the amount of oil supplied will cause a corresponding reduction in the combustion air supplied to the nozzle. These controlling arms 62 and 42 may be connected with automatic control mechanisms or be adjusted by hand as may be desired.

105 In conjunction with the burner nozzle 110 heretofore described, I provide a plate 7 which is intended to be secured to the front

wall of the furnace. This has a conical, inwardly projecting sleeve 70, of such size as to receive the conical portion of the nozzle and to provide an annular air inlet 5 channel 71, through which additional air for combustion is provided. The casing of the nozzle and the plate 7 are provided with complementary lugs or arms at 72 and 73, which may be secured together by bolt 74, 10 thereby making it possible to quickly and easily remove the nozzle for examination or adjustment. The oil supply to the nozzle is provided through a pipe 24.

In the operation of this device the oil is 15 fed through the channels 21, 22 and discharged to the inner end of the core 2. As discharged it is received upon the surface of the conical oil distributor 3, which is revolving. This throws the oil outwardly into 20 the annular blast of air under pressure which is being discharged through the annular opening between the cone 10 and the core 2. It is thereby blown out and atomized sufficiently to secure efficient ignition. 25 As an additional means of securing combustion, air under ordinary draft is permitted to flow through the annular channel 71, surrounding the conical pipe 10 of the nozzle. In consequence a thorough combustion of 30 the oil occurs.

I have provided means whereby the effective area of the port 61 of the oil control valve may be adjusted. This is done by adjusting the rod 60, in which this port is 35 formed, lengthwise in its receiving bore. To secure this the outer end of the rod is threaded and receives an adjusting nut 69. Also a threaded plug 66 is screwed into a 40 bore in the casing and contacts with the inner end of the valve rod 60, thereby limiting its inward position. This may be adjusted as desired so as to employ a portion of the length of the port 61 desired. A lock

nut 67 upon the plug 66 secures it firmly in adjusted position. At the opposite side 45 of the casing a packing sleeve 68 is employed to prevent leakage of oil.

The bore receiving adjusting plug 66 is extended sufficiently to accommodate a 50 spring 66' which bears against nut 69 to hold the rod 60 always in close contact with the adjusting nut 66'.

What I claim as my invention is:

1. An oil burner nozzle comprising a central core and a surrounding shell forming 55 an annular air supply channel, said core having radial arms connecting it with the outer shell, one of said arms and the core having passages for conveying oil to the inner end of the nozzle, said core having an axial 60 shaft-receiving bore which at its inner end is enlarged to include the discharge end of the oil supply channel, a shaft journaled in said core and a conical distributor head carried by said shaft, within the enlarged inner end of said core and with its large end 65 extending beyond the core end.

2. An oil burner nozzle comprising a central core and a surrounding shell spaced 70 radially outward therefrom to form an annular air channel, said core being centrally bored to accommodate a distributor shaft, 75 said bore at the inner end of the nozzle being enlarged, the upper wall of said core being provided with an oil discharge channel discharging into the enlargement of said bore, a shaft journaled axially of said core, a conical distributor head fixed to the inner 80 end of said shaft with its large end projecting from the bore of the core, and a fan fixed to the opposite end of the shaft with its vanes extending across the receiving end of the annular air supply channel.

Signed at Seattle, Washington, this 18th day of August, 1927.

WALTER B. FOGH.
